UNITED STATES PATENT OFFICE.

ASA S. LIBBY, OF EVERETT, ASSIGNOR TO THE BEAL LASTING MACHINE COMPANY, OF BOSTON, MASSACHUSETTS.

SHOE-LASTING MACHINE.

SPECIFICATION forming part of Letters Patent No. 317,384, dated May 5, 1885.

Application filed August 7, 1884. (No model.)

To all whom it may concern:

Be it known that I, ASA S. LIBBY, a citizen of the United States, residing at Everett, in the county of Middlesex and State of Massachusetts, have invented certain new and useful Improvements in Shoe-Lasting Machines, of which the following is a specification, reference being had therein to the accompanying drawings.

10 My invention relates to improvements in shoe-lasting machines.

The object of my invention is to produce a lasting-machine in which the reciprocating lasting-jaws, which close in to fold the vamp down over and onto the last at different or successive periods of time, are operated from a continuously-rotating shaft, or from a shaft adapted to be continuously rotated in one direction; and my invention is made with special reference to the patent granted Ezra F. Beal, May 15, 1883, No. 277,664; reissued February 26, 1884, No. 10,454.

My invention consists in connecting the clutch which engages with the eccentrics to a cam-faced wheel, whereby the clutch is automatically shifted from one eccentric to the other to operate the different jaws.

My invention consists, further, in certain novel devices for operating the last-support, as will more fully appear.

Referring to the drawings, Figure 1 is a vertical sectional view showing the cam-wheel for operating the clutch. Fig. 2 is a vertical sectional longitudinal view. Fig. 3 is a top or plan view of the Beal machine above referred to and as shown in Fig. 2 of his patent. Fig. 4 is a side view showing the hanger or clutch operating mechanism which engages with the cam-slot in the cam-wheel.

40 The main features of the machine—viz., the reciprocating slotted frame A, opening and closing side and toe jaws, B C, pitman D, eccentrics E and F, shaft G, and all the mechanism shown in Fig. 3 of the drawings—are identical with the machine as constructed under the Beal patent above referred to. In that patent, however, the toe and side jaws are operated by a pitman the eccentric of which is brought into engagement with a clutch, while 45 to operate the pitman which moves the side

toe and side heel jaws the clutch had to be shipped by hand to engage with the last-mentioned pitman, thus causing unnecessary delay in the lasting of a shoe.

By the devices embraced in this application 55 the shifting of the clutch from one eccentric to the other is done automatically, as will now be described in detail.

H is a shaft mounted in suitable bearings in the frame, directly underneath and parallel 60 with the shaft G, and receives motion therefrom by means of the pinion-wheels I and K.

L is a wheel or disk secured to the shaft H, in the periphery of which is formed a cam-groove to receive a friction-wheel, N, secured 65 to the end of the yoke O, which embraces the clutch P, said yoke being hung to an arm, R, secured to the frame of the machine in such a manner as to admit of the yoke swinging back and forth with the clutch. The yoke O is provided on its inside with pins, which engage with a groove formed in the periphery of the clutch.

It will be noticed that by the action of the cam-groove M on the yoke O the clutch will 75 be thrown into and out of engagement alternately with the eccentrics, and thus bring into action first the side and toe jaws, B C. The clutch will then be automatically shifted to engage with the eccentric F to bring into ac- 80 tion the side toe and side heel jaws.

T is the heel-support for the last, the lower end of which passes through a bracket, U, secured to the side pieces, V, said side pieces being secured to the cross-piece W of the 85 frame of the machine. The side pieces, V, are provided with diagonal tongues a, which fit into diagonal grooves b in the sliding block B'. The sliding block B' is provided with an opening, c, through which the lower end of 90 the jointed standard C' of the heel-support passes, said standard being provided with a collar, d, which rests on the top of the sliding block B'.

D' is a bell-crank lever pivoted at e to a 95 bracket, f, said bracket f being firmly secured to the frame of the machine.

E' is a rod or bar, one end of which is secured to the bell-crank lever D', the other end being secured to the sliding block B'. 100

It will be noticed that when the operator places his foot on the arm *g* of the bell-crank lever and forces it downward the sliding block *B'* will be drawn forward upon the inclined 5 tongues *a*, and thus the bar *C'*, with the last and shoe-vamp thereon, will be raised up, so that the clamping or crimping jaws of the machine will act on the vamp to crimp it down over the edges of the last. A reverse movement of the bell-crank lever will slide the block *B'* rearward, and thus lower the rod *C'* and last.

Having thus described my invention, what I claim, and desire to secure by Letters Patent, 15 is—

1. In a shoe-lasting machine, the combination, with the crimping-jaws, the eccentrics, jaw-actuating mechanism, and the continuously-rotating shaft, of the clutch and cam-20 wheel, whereby the clutch is automatically shifted to operate the mechanism to thrust the

jaws forward and backward in alternate series, substantially as specified.

2. The combination, with the clamping-jaws, the eccentrics, and driving-shaft, of the 25 shipping-clutch and its yoke suspended from a hanger, the friction-wheel mounted at the lower end of the yoke, and the cam-wheel mounted on an independent shaft, and the intergearing cog-wheels, whereby the parts are 30 operated automatically, as set forth.

3. In a shoe-lasting machine, the bell-crank lever *D'*, pivoted to the machine, and pitman or arm *E*, connected to the sliding block *B'*, as described, in combination with the standard 35 *C'*, as set forth.

In testimony whereof I affix my signature in presence of two witnesses.

ASA S. LIBBY.
